US0D1003711S

(12) **United States Design Patent** (10) **Patent No.:** **US D1,003,711 S**
(45) **Date of Patent:** **** Nov. 7, 2023**

(54) **TAMPER-EVIDENT BAG SEAL**(71) Applicant: **Inno-Pak, LLC**, Delaware, OH (US)(72) Inventors: **Denny V. Tao**, Katy, TX (US); **Nathan W. Schultz**, Westerville, OH (US); **Steven A. Mayer**, Indianapolis, IN (US)(73) Assignee: **Inno-Pak, LLC**, Delaware, OH (US)(***) Term: **15 Years**(21) Appl. No.: **29/848,360**(22) Filed: **Aug. 2, 2022****Related U.S. Application Data**

(60) Division of application No. 29/836,371, filed on Apr. 26, 2022, now Pat. No. Des. 970,339, which is a continuation-in-part of application No. 17/683,560, filed on Mar. 1, 2022, which is a continuation of application No. 29/725,476, filed on Feb. 25, 2020, now Pat. No. Des. 949,686, said application No. 29/836,371 is a continuation-in-part of application No. 29/725,476, filed on Feb. 25, 2020, now Pat. No. Des. 949,686, which is a continuation-in-part of application No. 29/707,037, filed on Sep. 25, 2019, now Pat. No. Des. 949,010.

(57) CLAIM

The ornamental design for a tamper-evident bag seal, as shown and described.

DESCRIPTION

FIG. 1 is a perspective view of a first embodiment of a tamper evident bag seal showing our new design;

FIG. 2 is a top plan view thereof;

FIG. 3 is bottom plan view thereof;

FIG. 4 is a cross-sectional view of figure along line 4-4 of FIG. 2;

FIG. 5 is a perspective view of the tamper evident bag seal of FIG. 1 shown in a partially folded configuration;

FIG. 6 is another perspective view of the tamper evident bag seal of FIG. 5;

FIG. 7 is a front elevation view thereof;

FIG. 8 is a rear elevation view thereof;

FIG. 9 is a left side elevation view thereof, the right side being a mirror image;

FIG. 10 is a top plan view thereof;

FIG. 11 is bottom plan view thereof;

FIG. 12 is another perspective view of the tamper evident bag seal of FIG. 1 shown as installed on an exemplary bag in a sealed configuration;

FIG. 13 is a front elevation view thereof;

FIG. 14 is a rear elevation view thereof;

FIG. 15 is a left side elevation view thereof, the right side being a mirror image;

FIG. 16 is a top plan view thereof;

FIG. 17 is another perspective view of the tamper evident bag seal of FIG. 12 shown as installed on an exemplary bag in an unsealed or tampered evident configuration;

FIG. 18 is a front elevation view thereof;

FIG. 19 is a rear elevation view thereof;

FIG. 20 is a left side elevation view thereof, the right side being a mirror image;

FIG. 21 is a top plan view thereof;

FIG. 22 is another perspective view of the tamper evident bag seal of FIG. 12 shown as installed on an exemplary bag in a partially unsealed or tampered evident configuration

FIG. 23 is a perspective view of a second embodiment of a tamper evident bag seal showing our new design;

FIG. 24 is a top plan view thereof;

FIG. 25 is bottom plan view thereof;

FIG. 26 is a perspective view of a third embodiment of a tamper evident bag seal showing our new design;

FIG. 27 is a top plan view thereof; and,

FIG. 28 is bottom plan view thereof.

In the drawings the dotted lines are for the purpose of illustrating perforations that form part of the claimed design. The dash-dash broken lines are shown for the purpose of illustrating both parts of the article as well as environmental subject matter and form no part of the claimed design.
